G. E. SPEAR.

THERMOSTATIC CIRCUIT CONTROLLER.

APPLICATION FILED APR. 11, 1913.

Patented Nov. 3, 1914.

UNITED STATES PATENT OFFICE.

GEORGE E. SPEAR, OF AMESBURY, MASSACHUSETTS, ASSIGNEE TO STANDARD THERMOMETER COMPANY, OF BOSTON, MASSACHUSETTS, A CORPORATION OF MAINE.

THERMOSTATIC CIRCUIT-CONTROLLER.

1,115,607.

Specification of Letters Patent.

Patented Nov. 3, 1914.

Application filed April 11, 1913. Serial No. 760,563.

To all whom it may concern:

Be it known that I, GEORGE E. SPEAR, a citizen of the United States, residing in Amesbury, county of Essex, and State of Massachusetts, have invented an Improvement in Thermostatic Circuit-Controllers, of which the following description, in connection with the accompanying drawings, is a specification, like letters on the drawings representing like parts.

This invention relates to a thermostatic circuit controller, especially adapted for controlling the opening and closing of the dampers of steam and hot water heaters, furnaces and the like, and has for its object to provide a simple, compact, efficient and inexpensive apparatus with which the temperature of a house or other building may be regulated and maintained at a substantially constant temperature.

The particular features of the invention will be pointed out in the claims at the end of this specification.

Figure 1 is a front elevation of an instrument embodying this invention. Fig. 2, a like view with the cover and glass removed. Fig. 3, an enlarged vertical section on the line 3-3, Fig. 1. Fig. 4, a section on the line 4-4, Fig. 3, looking in the direction of the arrow. Fig. 5, a rear elevation of the instrument, and Fig. 6, a diagram of circuits to illustrate the working of the instrument.

The instrument herein shown as embodying this invention is provided with a circular casing *a* having a cover *b* provided with a slot *c* behind which is located a glass disk *d*. The casing *a* contains a metal disk *e* suitably secured in fixed position within it and provided with a curved slot *f* and above the latter with a scale or series of graduations *g* indicative of degrees of temperature. In the present instance, the disk *e* is positioned within the casing by studs *h* secured to the rear wall of the casing and a ring *j*, which bears against the front face of the disk. The ring *j* is retained within the casing by the glass disk *d* and cover *b*. The metal disk *e* divides the casing into two chambers *m*, *n*, and has secured to its rear side a plate 12 and a yoke 13, which support a shaft 14, which is designed to be turned in opposite directions by a coiled thermostatic strip 16 whose convolutions are concentric, and which has one end attached to the shaft 14 and its other end to a stud 17

on the plate 12. The shaft 14 is extended through a hole in the disk *e* into the chamber *m*, and has attached to its front end a contact arm or member 20, whose upper end is extended between two circuit terminals 21, 22, which are adjustably carried by studs 23, 24 on the cross bar 25 of a T-shaped arm 26, which has integral with it at its longitudinal center a pointer 27, which co-operates with the scale or graduations *g*, and which has integral with it at its lower end a disk 30 provided with a plurality of gear teeth 31, which mesh with a pinion 32 on a shaft 33, supported by the disk *e* and by a cross bar 34 secured thereto as by screws 35. The disk 30 is mounted to turn on a hub 37 attached to the plate 12 and projected through a hole in the disk *e*, and is retained on the hub by a washer 38. The shaft 33 is turned by a handle 40, which is preferably detachable from the said shaft, and to this end is provided with a hollow stem or shank 41, which is adapted to be inserted through a hole in the cover *b* and fitted over the end of the shaft 33, which latter is provided with a longitudinally extended slot 42, into which passes a cross pin 43 within the hollow shank or stem 41, and by means of which the handle is engaged with the shaft so as to rotate the same when the handle is turned. The studs 23, 24 which carry the terminal screws 21, 22 are insulated from the cross bar 25 by strips 43 of mica or other suitable insulating material.

The studs 23, 24 are connected by insulated flexible conductors 44, 45 to fixed terminals 46, 47 extended through the back wall of the casing and having connected therewith continuations of the wires 44, 45, which form part of two circuits containing two electromagnets 50, 51, which are energized when the contact arm 20 makes contact with the terminal screws 21, 22.

The contact arm 20 is common to both circuits, which are diagrammatically shown in Fig. 6, and comprises line wires 52, 53, with one of which as 52 the contact arm 20 is connected by the wire 54, and with the other of which the electromagnets 50, 51 are connected by the wires 44, 45. The wire 54 is electrically connected with the contact arm 20, through the metal frame or spider 55, which is metallically connected with the casing *a* by the screws 56. The electromagnets 50, 51 are provided with

suitable armatures 57, 58, which are operatively connected in a manner well understood, with the mechanism (not shown) which operates the damper or other devices 5 to be controlled.

The glass disk *d* is broken away as at 60, Fig. 3, so as not to interfere with the handle 40.

In operation with the instrument herein shown, the handle 40 is turned so as to move the pointer 27 to the graduation *g* on the dial, which is indicative of the temperature at which it is desired the house or other building or a room therein should be heated. 10 The screws 21, 22 are adjusted at the factory with relation to the contact arm 20, so that the temperature may vary one or more degrees on either side of the degree with which the pointer registers. When the 15 temperature in the vicinity of the instrument rises above that at which the pointer rests, a sufficient amount, say one or two degrees, the contact arm 20 is brought into contact with the screw 21 and the circuit 20 of the magnet 44 is closed, thereby energizing the said magnet and operating the mechanism (not shown) to close the damper. When the temperature of the room falls below the desired temperature, say one or two 30 degrees, the contact arm 20 is brought into contact with the screw 22 and the circuit of the magnet 45 is closed, which energizes the same and effects the opening of the damper.

It will be observed that the pointer 27, 35 T-shaped bar 26 and toothed disk or gear 30 may be and preferably are made in one piece of metal, and may be stamped out of a piece of sheet metal, which serves to simplify and reduce the cost of the instrument. 40 So also it will be observed that the convolutions of the thermostatic strip are concentric, which enables the thermostat to be brought into close proximity to the disk *e* and thereby enables the instrument to be 45 contained in a shallow casing, which serves to make the instrument compact and also to reduce the cost.

By making the handle 40 detachable from shaft 33, liability of the pointer being turned 50 by unauthorized persons is reduced to a minimum.

Claims:

1. In an instrument of the class described, in combination, a casing, provided with a removable cover having an opening in it, 55 a glass disk within said casing covering said opening, a disk within said casing forming chambers within the casing, and provided with graduations in line with the opening in the cover, a plate secured to the rear side of said disk, a cross bar attached to said plate, a shaft supported by said cross bar and plate and extended through said disk, a thermostatic strip having a plurality of concentric convolutions located between said plate and cross bar and having one end secured to said shaft, a contact arm mounted on said shaft in front of said disk, circuit terminals between which said contact arm is extended, a T-shaped carrier 60 for said terminals having the latter secured to the cross bar of said carrier, a pointer integral with the said carrier and coöperating with said graduations, and a toothed disk integral with said carrier, a pinion in 65 mesh with said toothed disk, a shaft on which said pinion is mounted, and a handle on said shaft to turn it, substantially as described.

2. In an instrument of the class described, 80 in combination, circuit terminals spaced apart, a T-shaped carrier for said terminals having the latter secured to the cross bar of said carrier, a pointer extended from said cross bar and integral therewith, a toothed 85 disk integral with the vertical member of said carrier, means to rotate said toothed disk, a hub on which said disk is mounted, a shaft extended through said hub, a contact arm attached to one end of said shaft and 90 having its free end extended between said circuit terminals, and a thermostat connected with said shaft to rotate the same and move said contact arm, substantially as described. 95

In testimony whereof, I have signed my name to this specification in the presence of two subscribing witnesses.

GEORGE E. SPEAR.
